PROCESS FOR THE PRODUCTION OF PHOTO-LIKE MULTITONED PRINTS

Friedrich Lierg, Vienna, Austria, assignor to Jasma A. G., Zurich, Switzerland, a company of Switzerland

Application March 15, 1934, Serial No. 715,719
In Germany March 17, 1933

1 Claim. (Cl. 101—149)

Pictures, which cannot be distinguished from photographs, can be produced by the so-called suction method in which are used printing matrices consisting of colloidal substances either in the shape of an image relief or in the form of a layer tanned in a picture-like manner and produced by the action of light. Compared with the toned silver images, prints of the kind above mentioned have the advantage that they can be produced in a less expensive manner and that it is possible to select practically unlimited tones, while the tones are limited which can be obtained by the chemical toning of the silver images. Therefore the tone can be adapted to the characteristic of the picture and to the taste of the purchaser.

In the known suction printing methods, such as the pinatype, the Jos-Pe method and the like, in which the printing matrices are produced by the action of light, the time required for printing is very considerable in view of the slow transmission of the coloring matter, and therefore these methods cannot compete in the case of the production in large quantities with the method of copying on development paper. However besides this fact, they are not adapted for the production of series in different tones of colors, because during printing the entire coloring matter does not pass from the matrix into the printing paper, so that during the following printing with another color the remainder of the coloring matter participates in the printing to a considerable extent and therefore influences the intended color tone in an uncontrollable and frequently disadvantageous manner.

In view thereof it is necessary to take for every coloring matter a separate matrix or to work with color-destroying agents which however unfavorably influence the matrix.

Lately the suction method has been improved considerably, so that the printing operation is carried out in a few seconds and consequently the production in large quantities of monochrome or multi-tone prints is carried out in an economical manner. On the other hand by the idea of preparing the printing layer of the printing paper in such a manner that the dyestuff or any other coloring agent is precipitated in a water-insoluble manner when passing into this layer, it has been possible to transmit the entire dyestuff or coloring agent, imbibed in the matrix, from the latter, so that no residue of coloring matter remains behind which may detrimentally influence a print carried out in another color.

Applicable for the process according to the

present invention are particularly those suction printing methods in which, by a particular preparation of the gelatine relief or by a particular choice of the dyes, the same are bound in a water-insoluble manner and are set free again by the special preparation of the printing paper only, because the coloring is effected in a very short time by the artificially produced or already originally effective affinity between the gelatine-relief and the dye, so that also this procedure is carried out very quickly.

Also inorganic and organic electrolytes particularly metallic salts are absorbed very quickly by the gelatine-relief. If the printing paper is prepared in known manner with a precipitant for the metallic salt which jointly result in a correspondingly colored precipitate, the entire metallic salt solution is transmitted from the relief during the printing, so that printing can take place immediately with another metallic salt without the use of any intermediate washing.

An apparatus for carrying out the process according to the present invention is shown diagrammatically and by way of example in the accompanying drawing. The printing matrices used for this object can be produced either by the tanning development of exposed haloid silver emulsions for instance by means of pirochate-chine or by the action of a hardening bleacher and by washing in hot water. Also chromate gelatine layers can be hardened in picture-like manner by exposure behind a diapositive. These are a few examples only which are suitable for the production of printing matrices and do not form an essential part of the present invention.

As shown in the drawing, an endless band 1 of a flexible material, for instance a metal tape, celluloid band or the like, is provided with printing matrices. The band 1 is led over rollers 2, 3, 2', 3', 4', 5', 6', 7', 8', 4, 5, 6, 7, 8 and passes through four troughs 9, 10, 9', 10'. The troughs 9 and 9' are filled with solutions of for instance basic dyes for coloring the matrices, while the troughs 10 and 10' contain water for washing away the dye in excess. The printing paper 11 is coated with a gelatine layer containing a precipitant for the dye (for instance silico tungstic acid) and is in the form of a long band, which is wound up on a roller 12 and passes over rollers 13, 14 and through a trough 19 filled with water for wetting the band 11. The bands 1 and 11 are brought into intimate contact with each other between the rollers 2 and 16', 3 and 17, 2' and 16', and 3' and 17', whereby the entire dye contained in the matrices of the band 1 is trans-

mitted to the layer of the printing paper, because it is precipitated in the same in a water-insoluble manner. After leaving the rollers 3 and 17, the band 1 returns into the trough 9', while 5 the paper-band 11 is wound up on a roller 18. Thus the entire dye is removed from the matrices before they return into the trough 9 and therefore the latter can be filled without difficulty with another dye without the danger of obtaining 10 mixed colors such as it is the case for instance in connection with the known pinatype process. The dyeing of the matrices takes approximately one half minute, while the complete transmission of the dye from the matrix takes approxi- 15 mately one minute, and therefore provision is made that each matrix remains in the troughs 9 and 9' for approximately one half minute, while double the time is taken by the matrix during its movement with the printing paper being 20 tween the rollers 2 and 3'. For printing in two tones, thus pictures with soft lights and intense shades, use is made of the arrangement in the following manner. The trough 9' is charged with a basic dye for making the shades. The trough 25 9 is filled with dye for printing the lighter places. The rinsing water in the trough 10' is slightly acidified. A part of the dye of the matrix is again removed in the trough 10'. This removal influences mainly the thin places of the lights, 30 so that essentially the shades are printed only. Now the band 1' passes over the roller 20 and into the trough 9 in which the matrices are supplied with the other dye, which mainly determines the tone of the lights. In the trough 10, 35 the excessive dye is washed by water, which produces an alkaline reaction and therefore does not set free the basic dye in the gelatine but rather promotes the binding thereof.

If desired, a mixture of two dyes, for instance 40 rhodolinreinblau (Zeitschrift für Farben- und Textilchemie 1903, page 337, published by Wieg und Sohn, Braunschweig, Germany) and chrysoidin (Schultz No. 33), is charged into the trough 9', the dye (rhodolinreinblau) determin- 45 ing the tone of the shades being readily removed by washing, while the other dye (chrysoidin) belongs to that group of basic dyes which together with the gelatine of the printing matrix form a completely waterproof combination. One of the 50 dyes is washed out of the thin places of the picture in the trough 10, so that these places print only the tones of the other dye, while the shade-tones are determined mainly by the more readily washed out dye or by the mixture of both dyes. 55 In this case the arrangement 2 to 10 is not in use or it can be used as a separate printing device provided with its own paper-feed.

The trough 10 is filled, for instance, with potassium ferrocyanid, while the troughs 9, 9' and 60 10' remain unused, if electrolytic solutions are

used for printing. In this case a water bath is not used for removing the adhering solution, because the same would completely wash out the electrolytic solution from the matrix. The adhering solution is removed for instance by elastic 5 wipers 21, disposed between the rollers 8 and 2. Similar wipers 22 are arranged for removing any adhering water from the paper 11 between the rollers 14 and 15. The colloidal layer of the paper is treated for instance with a ferric salt 10 and uranates. This results in pictures ranging from olive-brown to olive-green, the shades being more brownish and the lights more bluish. A printing paper with two layers, each containing different precipitants, results in the pro- 15 duction of double tones. If the bottom layer contains for instance a ferric salt and in case the top layer embodies a certain quantity of a uranate and if potassium ferrocyanide is used for print- 20 ing, the result will be a reaction of the entire potassium ferrocyanide with the uranate in the light places of the picture, so that brownish lights are produced. In the dark parts of the shades, the matrices contain such a quantity of potassium ferrocyanide that the same does not fully react 25 with the limited quantity of uranate. The rest of potassium ferrocyanide reacts with the ferric salt of the bottom layer and forms Prussian blue which transforms the brown of the shades into 30 a black or bluish black tone.

In all cases, the printing can be carried out according to the described methods also by other arrangements or even by hand. In view of the ready application of the coloring agent it is not necessary to bathe the matrix in the solution, 35 but the same can be applied to the matrix by means of a brush, cotton or the like if necessary by the aid of stencils, so that the individual parts of the picture can be made in different tones 40 of color. Matrices prepared for single or multi-tone prints can be influenced at individual places by the application of color.

What I claim is:—

Process for the production of photo-like mul- 45 ti-toned prints by means of a gelatin matrix and by using a printing surface prepared with a re- agent which precipitates coloring agents in a water-insoluble form, which consists in first applying two coloring agents precipitatable by said reagent to the matrix, one of said coloring agents 50 being irremovable while the other coloring agent is removable by washing, then partly removing said removable coloring agent, hereafter placing in contact said printing surface with said matrix whereby both coloring agents are transferred 55 from said matrix to said printing surface, and finally separating said matrix and said printing surface.

FRIEDRICH LIERG. 60
